VENTILATED BODY SUPPORT

Charles Edward Lenz, Jr., Baltimore, Md.

Application May 18, 1934, Serial No. 726,419

8 Claims. (Cl. 5—347)

This invention relates to new and useful improvements in ventilated body supports, such as mattresses and cushions of the inner spring type.

Among the several objects of my invention are to provide means contained within the mattress or other body support for effecting a proper ventilation thereof upon downward pressure exerted against the mattress followed by a release of such pressure; to provide a ventilating arrangement for a mattress wherein one or more bellows are located within the mattress and function to draw into the bellows a volume of screened air on release of pressure from the mattress and to discharge said air from the bellows into the interior of the mattress upon pressure being exerted thereon; to provide one or more bellows which can be readily mounted between the springs of the mattress without reducing the number of the springs or without changing the usual arrangement thereof, and to provide such a device which is simple in construction, positive in operation, and cheap to manufacture.

With these and other objects in view which will more fully appear, the nature of the invention will be more clearly understood by following the description, the appended claims, and the several views illustrated in the accompanying drawings.

In the drawings:

Figure 1 is a plan view of a mattress constructed in accordance with my invention, a portion of the covering being broken away to better disclose my invention.

Figure 2 is a vertical longitudinal sectional view taken on the line 2—2 of Figure 1.

Figure 3 is a vertical cross sectional view taken on the line 3—3 of Figure 1.

Figure 4 is a plan view of one of the bellows, Figure 5 is a plan view of a mattress showing a modified arrangement of the bellows.

Figure 6 is a similar view but showing a further modification.

Figure 7 is a plan view of a still further modification of a bellows.

Figure 8 is an enlarged sectional view showing the air inlet construction for the bellows.

Figure 9 is a detailed sectional view showing the air outlet construction for the bellows.

Figure 10 is an enlarged detail view showing the bellows being connected to the top and bottom of a spring.

Figure 11 is a plan view of a wire screen used in connection with the air inlet valve, and

Figure 12 is a plan view showing a fabric screen associated with the air inlet valve.

Referring to the accompanying drawings, my invention includes an inner coil body support A such as a mattress or cushion, which comprises the usual rectangular wire frame 5 which supports a plurality of coil springs 6 in the usual manner, said springs being arranged in the usual longitudinal and transverse rows. This spring unit is completely enclosed by a cover B which comprises an intermediate layer 7 of felt, hair, or sisal, or the like, and inner and outer layers 8 and 8^a of canvas or the like.

By reference to Figures 1 to 4 particularly, I have positioned one or more bellows C between certain longitudinal rows of springs 6. As shown in Figures 1, 2 and 3, there are three of these bellows, one being centrally disposed with respect to the frame and the other two being located adjacent the sides of the frame. Each bellows is formed of a fabric which is impervious to the passage of air. The bellows is relatively narrow and extends substantially throughout the length of the frame A and has a depth substantially equal to the height of the spring 6. Attached to the bellows is an air inlet tube 9 which communicates with the interior of the bellows and with the atmosphere at a point exteriorly of the mattress. Mounted in the tube 9 is an air inlet valve 10 of the spring ball type which permits air to enter the bellows but prevents air from discharging therethrough. A tube 11 extends through the cover B and is secured thereto by any suitable means. The air inlet tube 9 projects outwardly into the tube 11. The tube 11 projects exteriorly of the cover B and is provided with a threaded end for receiving a cap 12 having an air inlet opening 13 and a resultant inwardly extending flange 14. A wire screen 15 and a fabric screen 16 are placed against each other and are located between the air opening 13 and the outer end of the tube 11, said screens 15 and 16 being removably clamped in position between the flange 14 and a ring gasket 17 which bears against the outer end of the tube 11. Each bellows C is provided with one or more air outlet tubes 18 in which is mounted an air valve 19 of the spring ball type whereby air may be forced outwardly from the bellows but will be prevented from entering the same. Each bellows C is secured at its top and bottom to the top and bottom portions of the adjacent springs by tacking 20 and 21 respectively or by any other suitable means. Thus when a spring is compressed the bellows will be correspondingly compressed and when pressure is re-

leased from the spring the bellows will return to its normal position.

From the foregoing it will be observed that whenever a person exerts a downward force 5 against the mattress the springs 6 will be compressed as well as the adjacent bellows and as a result air which has been previously drawn into the bellows through the air valve 10 will be discharged from the bellows into the mattress 10 through the air outlet valve 18, and when said pressure is released from the mattress the spring 6 and the bellows C will return to their normal positions thereby drawing into the bellows a new supply of screened air through the air inlet valve 10. 15

18 In Figure 5 I have illustrated a modified arrangement of the bellows. In this form I have disclosed three bellows which are arranged between adjacent transverse rows of springs, one of the bellows being centrally located while the 20 other two are located adjacent the ends of the mattress.

In Figure 6 I have disclosed a further modification of the bellows wherein a single bellows D is provided. This bellows is H-shaped in plan view and includes two sections 22, 22 which extend longitudinally of the mattress and a transverse connecting portion 23 which is integral with the sections 22, 22. 25

In Figure 7 I have disclosed a still further modification of a bellows. In this form the bellows comprises three longitudinal sections 24, 25 and 26 which are integrally connected at their ends to transverse sections 27, 28.

It is of course to be understood that the details of structure and arrangement of parts may be variously changed and modified without departing from the spirit and scope of my invention.

I claim:

40 1. In a ventilated spring body support, the combination with a frame having a plurality of coil springs, of a fabric cover enclosing the same, a bellows mounted within the cover, said bellows being provided with a valved inlet for receiving air from the exterior of the cover upon expansion of the bellows and with an independent valved outlet for directing the air from the bellows into the interior of the support upon collapsing of the bellows, and means to cause the bellows to be collapsed and expanded concomitantly with the compression and expansion of said springs. 45

2. In a ventilated spring body support, the combination with a frame having a plurality of coil springs arranged in parallel rows, of a fabric cover enclosing the same, a bellows mounted within the cover and between a pair of rows of said springs, said bellows being provided with a valved inlet for receiving air from the exterior of the cover upon expansion of the bellows and with a 50 valved outlet for directing the air from the bellows into the interior of the support upon collapsing of the bellows, and means to cause the bellows to be collapsed and expanded concomitantly with the compression and expansion of said springs. 55

3. In a ventilated spring body support, the combination with a frame having a plurality of coil springs arranged in transverse and longitudinal rows, of a fabric cover enclosing the same, a 70 plurality of bellows mounted within the cover and between certain of said rows of springs, each of said bellows being provided with a valved inlet for receiving air from the exterior of the cover upon expansion of the bellows and with a valved outlet for directing the air from the bellows into 75

the interior of the support upon collapsing of the bellows, and means to cause the bellows to be collapsed and expanded concomitantly with the compression and expansion of said springs. 5

4. In a ventilated spring body support, the combination with a frame having a plurality of coil springs arranged in transverse and longitudinal rows, of a fabric cover enclosing the same, a plurality of bellows mounted within the cover and between certain of said rows of springs, each of said bellows being provided with a valved inlet for receiving air from the exterior of the cover upon expansion of the bellows and with a valved outlet for directing the air from the bellows into the interior of the support upon collapsing 15 of the bellows, at least one of the bellows being located between a pair of longitudinal rows of springs and extending substantially throughout the length of the support, and at least another of the bellows being located between a pair of 20 transverse rows of springs and extending substantially throughout the width of the support, and means to cause the bellows to be collapsed and expanded concomitantly with the compression and expansion of said springs. 25

5. In a ventilated spring body support, the combination with a frame having a plurality of coil springs, of a fabric cover enclosing the same, and a bellows mounted within the cover, said bellows being formed of fabric impervious to the 30 passage of air and provided with a valved inlet for receiving air from the exterior of the cover upon release of pressure from the bellows and with a valved outlet for directing the air from the bellows into the interior of the support upon pressure exerted on the bellows, said bellows being anchored to the tops and bottoms of certain of said springs and so proportioned relatively to said spring as to be positively expanded and collapsed by movement of said springs. 40

6. In a ventilated spring body support, the combination with a frame having a plurality of coil springs arranged in parallel rows, of a fabric cover enclosing the same, a bellows member positioned within the cover and extending longitudinally between rows of said springs, said bellows being provided with a valved inlet for receiving air from the exterior of the cover upon release of pressure from the bellows and with a valved outlet for directing the air from the bellows into the interior of the support when pressure is exerted on the bellows, and means other than natural resistance of the bellows to deformation to positively cause the bellows to expand and collapse as said springs extend or are compressed 50 by release or application of body pressure. 55

7. In a ventilated spring body support, the combination with a frame having a plurality of coil springs arranged in parallel rows, of a fabric cover enclosing the same, a bellows member positioned within the cover and extending longitudinally between rows of said springs, said bellows being provided with a valved inlet for receiving air from the exterior of the cover upon release of pressure from the bellows and with a 60 valved outlet for directing the air from the bellows into the interior of the support when pressure is exerted on the bellows, and means to anchor portions of the bellows to portions of said springs, said bellows being so proportioned relatively to said springs that the anchoring of portions of the bellows will cause it to expand and collapse as said springs extend or are compressed 65 by release or application of body pressure. 70

8. In a ventilated body support comprising a 75

hollow collapsible padded body, means within the body to yieldably retain the shape of the body, a bellows within the hollow of the body and having back-check valve communication between the bellows interior and the exterior of the padded body and like independent communication between the interior of the bellows and the interior of the padded body, and means to cause the

bellows to collapse and expand concomitantly with the compression and expansion of the padded body whereby to draw air into the bellows and to thereafter forcibly expel it into the interior of the padded body for ultimate egress only 5 through the walls of the padded body.

CHARLES EDWARD LENZ, JR.
